[57] **CLAIM**

The ornamental design for a combined motorcycle trim rail and lighting unit, as shown and described.

DESCRIPTION

FIG. 1 is a top plan view of a combined motorcycle trim rail and lighting unit showing our new design, it being understood that the broken lines are for illustrative purposes only;

FIG. 2 is a front right side perspective view thereof;

FIG. 3 is a front left side perspective view thereof;

FIG. 4 is a rear left side perspective view thereof;

FIG. 5 is a rear right side perspective view thereof;

FIG. 6 is a rear elevational view thereof;

FIG. 7 is a left side elevational view, the right side elevational view being a mirror image thereof;

FIG. 8 is a front elevational view thereof; and

FIG. 9 is a bottom plan view thereof.
